Horace L. Campbell,
BY

Hugh K. Wagner,
ATTORNEY.

UNITED STATES PATENT OFFICE.

HORACE L. CAMPBELL, OF ST. LOUIS, MISSOURI.

ELEVATOR.

Application filed June 6, 1921 Serial No. 475,284.

To all whom it may concern:

Be it known that I, HORACE L. CAMPBELL, a citizen of the United States, residing at the city of St. Louis, in the State of Missouri, have invented certain new and useful Improvements in Elevators, of which the following is a specification.

This invention is illustrated in the drawings in the form of an elevator, but the construction is adapted for various useful purposes, among which may be mentioned, for the purpose of examples but not for the purpose of exhaustive enumeration, bookcases, wardrobes, grocery and other bins, and receptacles for the storage of stocks of merchandise for retail and other stores. It may be used, also, for airplane bodies for the reception of a load or passengers.

The main idea of the invention is to provide a plurality of receptacles suitably connected to a central shaft or rotating means in such a manner that the said receptacles will be maintained in a fixed relation thereto, and by which the contents of the said receptacles will not be tilted or tipped or shaken or dislodged, but when once placed in such a receptacle are maintained in a stable condition on the same level.

In the case of elevators, the goods or articles are placed in the receptacles for the purpose of being raised or lowered from one floor or level to another. In the case of use of this invention for the storage of merchandise or as a bookcase, the object is to increase the floor space by moving a receptacle, the contents of which is not in immediate demand, upward and out of the way while some other receptacle is in immediate use, but with the potentiality that the removed receptacle can be easily returned to a position where it can be most easily reached by the user.

This device may be constructed of any size according to the purpose for which it is intended. It may be comparatively small, or it may be large enough to carry articles from floor to floor in a tall building.

One use of this device that is especially important is in handling baggage or express matter at a railway station, where, if desired, it can be mounted on wheels or rollers and moved adjacent to an express or baggage car, and there receive such matter and elevate the same to a higher runway,

platform, or floor, where it can be more easily handled than on the walkway used by passengers and others.

In the accompanying drawings forming part of this specification, in which like numbers of reference denote like parts wherever they occur,

Figure 1 is an end elevation of an embodiment of the invention;

Figure 2 is a side elevation; and

Figure 3 is a fragmentary enlarged sectional view taken on the line 3—3 in Figure 2, looking in the direction indicated by the arrows.

A suitable frame, preferably of angleirons or the like, is provided, consisting of uprights 1, cross-pieces 2, and braces 3. The framework shown in Figure 1 is duplicated at the other side (or end) of the structure, as shown in Figure 2.

Braces 3 are fastened to the housing 4, and in conjunction with braces 17 support the same at approximately the center of the frame work. The lower braces 17 are the principal supports for housing 4, but are assisted in such support by the lower braces 3. The upper braces 3 and 17 act as supports and steadyng members for the housing. It is to be understood that the braces 3 and 17, as shown in Figure 1, are duplicated on the opposite side of the machine.

A plurality of storage receptacles 6 is provided, the same being adjusted to rotate with the pair of rings 7 that, within the above-mentioned frame, form the end members of the mechanism.

Each receptacle 6 bears a ring 8 fastened thereto by screws 9 or other suitable means. Each ring 8 is formed like an angleiron, so as to provide track 10 for roller 11 and track 12 for roller 13. Rollers 11 and 13 are both supported from the same bracket 14 attached by screws 15 to brace 16.

Braces 16 are bolted to braces 17. Braces 17 are attached at one end by bolts 18 to ring 7, and at the opposite end by bolts 19 to gear 22. Bolts 20 fasten the external spur gear 21 stationary to the frame 3. There is provided an external spur gear 21 and an internal spur gear 22. Spur gear 22 is so formed that roller 23 tracks on one face thereof and roller 24 on another face thereof. It is to be understood that there is a plurality of

rollers 23 and a plurality of rollers 24, the same being borne by arms 25 fixed to the side walls of housing 4 by screws 26.

The entire mechanism is driven from central shaft 27, which primarily actuates gear 28, which meshes with and drives spur gear 29. This meshes with internal spur gear 22 and drives the same, the external spur rack 21 meshing with and driving the spur pinions 30, mounted by shafts 31 on frame 32, attached by bolts 33 to braces 17. Pinions 30 mesh with and drive the spur gears 34, attached by bolts 35 and angleirons 36 to the receptacles 6. The receptacles 6 are so attached to gears 34 that they do not swing therein but rotate therewith. The housing 4 remains stationary at all times. The arrows indicate the direction of rotation of the various parts.

20 The dimensions of gears 34 are calculated with relation to the dimensions of rings 7, so that while rings 7 are revolving, the equilibrium of the contents of receptacles 6 is maintained on an even level therein because of the rotation of gears 34. From the central driving pinion or gear 28 to the outward extremities of the train of gears, including rings 7 and gears 34, the mechanism is planetary in its nature.

30 Rings 7 are caused to revolve by reason of their being connected by braces 17 to frame 32, which is driven by the inner spur gear 22 and gear 29.

Braces 38 are attached to braces 17, and 35 each brace bears rollers 39 and 40, which run on tracks 10 and 12 on gears 34.

The rollers 23 and 24 are intended for anti-friction purposes. It is to be understood that gears 34 and gear 22 are so formed, 40 angular in cross-section, that two tracks thereon are formed, on which the above-mentioned various anti-friction rollers run.

The shaft 27 is driven by motor 41 or any other suitable source of power, in a small 45 device, such as a bookcase for instance, a hand crank could be attached to shaft 27.

There is a plurality of rings 7 and receptacles 6 extending from one ring to the other, the whole forming a rotary frame. 50 Preferably both ends of receptacles 6 are open.

The receptacles 6 are not mounted on shafts or other supporting means, but are held in position by rollers 11 and 13, and 55 39 and 40, which prevent gears 34 from moving longitudinally or laterally or otherwise than rotarily.

In the drawings I have shown the ring 7 driven from the inside or from the central receptacle but it is obvious that the 60 source of power may be located without the rings 7 at any point on its circumference but this would necessitate a much larger gear around the circumferential area of ring 7

than the preferred form of internal spur 65 gear 22 shown.

It should be clearly understood from the foregoing that the external spur gear 21 is stationary with reference to the frame 3 and imparts motion to the idler 30 only 70 from travel of the idler 30 around external spur gear 21.

In airplane bodies, a heavier load in one receptacle 6 will result in causing equilibrium of other receptacles 6 by forcing 75 them by gravity to equalize the weights in all, tending to equal distribution of weight in all parts of the body. Ordinarily a brake will hold the receptacles 6 stationary, but this brake will be released when rising in 80 the air.

In case the ends of receptacles 6 are closed and a side thereof left open, beveled gears may be substituted for spur gears 34 and will preferably be attached at the said ends. 85

Beveled gears may be substituted throughout for the spur gears shown in the drawings.

Having thus described this invention, I hereby reserve the benefit of all changes in 90 form, arrangement, order, or use of parts, as it is evident that many minor changes may be made therein without departing from the spirit of this invention or the scope of the following claims:

95 I claim:

1. The combination of a central driving shaft, a gear driven thereby, an idler gear, an internal spur gear and an external spur gear, the said idler gear meshing with the 100 said internal gear, a frame driven by the said gears, and a plurality of receptacles borne by the said frame.

2. In a machine of the character described, the combination of a central housing, braces attached thereto, a normally stationary frame work braced by the said braces, a pair of revoluble rings, independent receptacles borne by the said rings, and means for driving the said rings and said 110 receptacles.

3. In a machine of the character described, the combination of a normally stationary frame, supporting a pair of rings having an angular construction in cross-section, a plurality of receptacles borne by the 115 said rings, gears attached to the receptacles and angular in cross-section, a plurality of rollers adapted to ride on tracks on the said rings, the said tracks being formed by the 120 said angular construction, and means for rotating the said rings, and independently rotating the said receptacles.

4. In a machine of the character described, the combination of a normally stationary frame, supporting a pair of rings having an angular construction in cross-section, a plurality of receptacles borne by the 125

said rings, gears attached to the receptacles and angular in cross-section, a plurality of rollers adapted to ride on tracks on the said rings, the said tracks being formed by the 5 said angular construction, a means for rotating the said rings, and independently rotating the said receptacles, and the said rollers being adapted to ride on the said 10 rings at substantially a right-angle each to its mate.

5. In a machine of the character de-

scribed, the combination of a normally stationary frame supporting a pair of rings, a plurality of receptacles borne by the said rings, gears attached to the receptacles, a 15 plurality of rollers adapted to ride on said rings, and means for rotating the said rings and independently rotating the said receptacles.

In testimony whereof I hereunto affix my 20 signature.

HORACE L. CAMPBELL.
